UNITED STATES PATENT OFFICE.

HARRY FEDER, OF NEW YORK, N. Y.

DESIGN FOR SKIRT-BINDING.

SPECIFICATION forming part of Design No. 29,350, dated September 13, 1898.

Application filed July 30, 1898. Serial No. 687,364. Term of patent 14 years.

To all whom it may concern:

Be it known that I, HARRY FEDER, a citizen of the United States, and a resident of New York, in the county and State of New York, have invented and produced a new and original Design for a Skirt-Binding, of which the following is a specification, reference being had to the accompanying drawings, forming a part thereof.

10 The essential feature of my design consists in a skirt-binding presenting in side elevation a head portion having the appearance of a woven fabric, an edge portion having the appearance of a brush or fringe, a portion of 15 the head being embellished by a change in the weave, producing a distinctive band or stripe presenting the appearance of lines of dashes arranged in staggered order.

In the accompanying drawings, Figure 1 is

a view of a piece of the skirt-binding in side elevation, and Fig. 2 is a view of the same in end elevation.

A represents the head, having the appearance of a woven fabric; C, the edge, having the appearance of a brush or fringe, and B ²⁵ the distinctive band or stripe, presenting the appearance of lines of dashes arranged in staggered order.

What I claim is—

The design for a skirt-binding, substantially as herein shown and described.

In testimony that I claim the foregoing as my invention I have signed my name in presence of two witnesses.

HARRY FEDER.

Witnesses:

FREDK. HAYNES,
EDWARD VIESER.
